ADJUSTABLE CHUTE FOR BUTTON FEEDERS

Oscar Halbreich, Forest Hills, N.Y., assignor to Kem Button Corporation, Brooklyn, N.Y., a corporation of New York

Filed Dec. 29, 1958, Ser. No. 783,535

2 Claims. (Cl. 193—38)

This invention relates generally to the field of feeding of small objects to a point of operation upon the same, and more particularly to an improved chute particularly adapted to be used in conjunction with a button feeder used in commercial sewing operations. Devices of this type are generally known in the art, and the invention relates to specific constructional details whereby adjustment of the same for use in connection with buttons of a variety of sizes is facilitated.

In button feeders of the class described, the chute is normally fed from a hopper means which keep the chute filled throughout substantially its entire length, buttons moving under the action of gravity and/or mechanical assist means to a point of ejection where a sewing operation is performed. In order to prevent the overlapping of buttons within the chute, and an accompanying sticking of buttons resulting from the overlapped condition, it is necessary that the walls of the chute correspond dimensionally to the overall dimensions of the individual buttons. Where only a single size and shape of button is employed, the design of chutes of this type is a relatively simple matter. However, where commercial practice requires the use of a wide variety of shapes and sizes of buttons, it is necessary to readjust the width of the chute with each change of button size and shape. In the prior art devices, this adjustment has required substantial shutdown time during the individual adjustment of a large number of points along the length of the chute, and in some cases, replacement of entire length of the chute with similar lengths having the required adjustment.

It is therefore among the principal objects of the present invention to provide an improved chute construction in which the abovementioned disadvantages have been substantially eliminated.

Another object of the invention lies in the provision of improved button chute construction which may be readily and conveniently adapted for use with a wide variety of button shapes and sizes by the operator of the sewing machine with which the device is used, by the simple turning of a relatively small number of adjustment screws.

Still another object of the invention lies in the provision of improved chute construction of the class described, and possessed of the above advantages in which the cost of fabrication may be of a reasonably low order, with consequent wide sale, distribution and use.

A feature of the invention lies in the particular adaptability of the invention to the feeding of shank-type buttons which are widely used in lower cost commercial sewing operations.

Another feature of the invention lies in the ready adaptability of the device to existing button feeders currently in wide use in the art.

These objects and features, as well as other incidental ends and advantages, will become more clearly apparent during the course of the following disclosure, and be pointed out in the appended claims.

2

On the drawings, to which reference will be made in the specification, similar reference characters have been employed to designate corresponding parts throughout the several views.

5 Figure 1 is a fragmentary view in perspective of an embodiment of the invention.

Figure 2 is a fragmentary enlarged view in perspective showing the upper portion of Figure 1.

10 Figure 3 is a fragmentary enlarged view in elevation showing the central portion of Figure 1.

Figure 4 is a fragmentary enlarged view in perspective showing the lower portion of Figure 1.

Figure 5 is a fragmentary top plan view as seen from the plane 5—5 on Figure 4.

15 Figure 6 is a vertical sectional view as seen from the plane 6—6 on Figure 2.

Figure 7 is a vertical sectional view as seen from the plane 7—7 on Figure 4.

20 Figure 8 is an enlarged vertical sectional view as seen from the plane 8—8 on Figure 4.

Figure 9 is an enlarged sectional view corresponding to that seen on Figure 8, but showing an adjusted relative position of certain of the component parts.

25 Figure 10 is a fragmentary rear elevational view as seen from the plane 10—10 on Figure 5.

In accordance with the invention, the device, generally indicated by reference character 10 is shown in Figure 1 in conjunction with a conventional button hopper 11. The device is interconnected with a conventional button 30 sewing machine, preferably as disclosed in my prior Patent No. 2,843,069 granted July 15, 1958, entitled "Shank Button Feeders." The device 10 comprises broadly: a base member 14, a plurality of track forming members 15 and adjustable supporting means 16.

35 The base member 14 is preferably formed from flat strip metal of suitable mechanical strength and rigidity, and includes an upper end 19 into which buttons are successively fed by the hopper means 11, and a lower end 20 having a discharge opening, preferably of the 40 type disclosed in the above mentioned patent. As best seen in Figure 1, the base member is generally elongated in configuration, and includes an upper edge 21, a lower edge 23, a forward or inner surface 24 and a rearward or outer surface 25.

45 The track forming members 15 are also formed from flat strip metal, and are substantially similar and arranged in relatively parallel disposition. Each includes an upper edge 28, a lower edge 29, a forward or outer surface 30 and a rearward or inner surface 31. The 50 members 15 are maintained in generally parallel disposition by the means 16, and form an elongated space therebetween generally indicated by reference character 32. The width of the space 32 is substantially constant throughout the length of the device 10, and is governed by the width of shanks 33 of buttons 34 with which the 55 device is used. At the present state of the art, it is customary to form shank buttons of varying sizes, shapes and designs with shank portions of relatively uniform dimensions, although, if desired, means for adjusting the 60 relative distance between the members 15 may be provided.

The adjustable supporting means 16 includes an upper support element 37, a median support element 38 and a lower support element 39. The upper support element 37 includes a first relatively fixed hinge arm 41 mounted on the surface 25 of the base member 14, the same being interconnected with a relatively moveable hinge arm 42 by a pin 43. The free end 44 of the moveable hinge arm 42 is provided with pin or rivet means 45 which secures the track forming members 15 to the inner surface thereof. An adjustment screw 46 inter-

connects the hinge arms 41 and 42, the same being provided with a finger engaging knob 47 and a threaded portion 48 engaging a threaded bore 49 in the hinge arm 41. As best seen in Figure 6, the hinge arms 41 is of curved configuration, including a first portion 50 and a second portion 51 joined by a bend portion 52. It will be observed that the axis of the pin 43 lies in a plane passing through the path of travel of successive shank portions 33 of the buttons 34, so that during adjustment the movement of the free end 44 may be considered to be substantially in a plane perpendicular to the plane of the base member 14.

The median support element 38 is generally similar to that of the upper support element 37, and includes a fixed hinge arm 55, and a moveable arm 56, the lower end 57 of which is engaged with portions of the track forming members 15 in a like manner.

The lower support element 39 includes a plurality of adjustment screws 60, 61 and 62, all of which cooperate to support a substantially rectangular frame 64 in threaded association with respect to the base member 14. The frame 64 supports a pair of track guide members 65 and 66 by pin means 67 which form continuations of the track forming members 15 to lead buttons 34 to the point of discharge.

The distance between the track guide members 65 and 66 and the inner surface 24 of the base member is variable independently of the adjustment between the track-forming members 15 and the inner surface, as the adjustment is preferably more critical at or near the point of discharge. Particularly where a button ejection assist is employed of the type disclosed in the above-mentioned patent, No. 2,843,069, the clearances are substantially less than where movement of the buttons is obtained solely by the action of gravity. This adjustment is made by first adjusting the elements 37, 38 and 39 in succession, by manually inserting a button at the upper end of the chute, with the elements 37, 38, 39 adjusted at minimum clearance. They are then progressively opened to permit the button to travel downwardly under the influence of gravity. Upon reaching the lower element 39, the clearance is adjusted using adjustment screws 60 and 61 to approximate clearance. As the test button travels to the lowest portion of the chute, final adjustment of the screw 62 will cause pivoting of that portion of the frame 64 indicated by reference character 70 about an axis disposed in a plane passing through the screws 60 and 61.

As the normal distance from the lower end of the chute to the last-mentioned plane is substantially greater than the normal distance from the axis of screw 62 to the plane, a relative small adjustment of the screw 62 results in a correspondingly greater adjustment of the ends of the members 65 and 66. As a final adjustment, the screws 60 and 61 are again tested using a second button to correct any small misalignment induced by the adjustment of the screw 66. In this manner, the lower end of the chute may be free of adjustment structure while yet obtaining an accurate adjustment of the entire length of the chute.

Referring to Figure 8 on the drawing, there is shown an adjustment of the lower support element 39 to accommodate a button having a relatively thick body, during which time the distance between the frame 64 and

the base member 14 is relatively enlarged. In Figure 9, there is shown an adjustment of the same structure to accommodate a button of relatively thin cross-section, during which time the distance between the frame 64 and base member 14 is diminished.

It may thus be seen that I have invented novel and highly useful improvements in chute construction for use in connection with the feeding of buttons from a supply hopper means to a point of sewing, in which means has been provided for the rapid adjustment of the effective width of the chute to accommodate buttons of varying widths. Although the specific embodiment shown relates to the feeding of shank buttons, with minor modifications (not shown) the construction may be employed in the feeding of sew-through-type buttons as well, in each case the relative width of the chute being regulated by the simple turning of a few threaded adjustments.

I wish it to be understood that I do not consider the invention limited to the precise details of structure shown and set forth in this specification, for obvious modifications will occur to those skilled in the art to which the invention pertains.

I claim:

1. In an adjustable track for use in conjunction with a button feeding device or similar structure, the improvement comprising: a base member of generally elongated planar configuration, a pair of elongated track forming members defining a track therebetween and disposed in substantially mutually parallel relation with respect to said base member, a first hinge arm mounted upon said base member and extending from said base member in a direction toward said track members, a second hinge arm interconnected with said track members substantially at a first end thereof and pivotally interconnected with said first hinge arm at a second end of said hinge arm, and threaded means interconnecting said second hinge arm and said base member for adjusting the relative position of said track forming members with respect to said base member.

2. In an adjustable track for use in conjunction with a button feeding device or similar structure, the improvement comprising: a base member of generally elongated planar configuration, a pair of elongated track forming members defining a track therebetween and disposed in substantially mutually parallel relation with respect to said base member, a first hinge arm mounted upon said base member and extending from said base member in a direction toward said track members, a second hinge arm interconnected with said track members substantially at a first end thereof and pivotally interconnected with said first hinge arm at a second end of said hinge arm, and threaded means interconnecting said second hinge arm and said base member for adjusting the relative position of said track forming members with respect to said base member; said threaded means being disposed intermediate said track forming members and the hinged interconnection of said first and second hinge arms.
